UNITED STATES PATENT OFFICE.

JOSEPH H. STEVENSON, OF HEWLETT, NEW YORK, ASSIGNOR TO AUTOMATIC RETAILING CORPORATION, A CORPORATION OF NEW YORK.

DESIGN FOR A HANDLE FOR VENDING MACHINES OR THE LIKE.

Application filed January 17, 1929. Serial No. 29,659. Term of patent 3½ years.

To all whom it may concern:

Be it known that I, JOSEPH H. STEVENSON, a citizen of the United States, and a resident of Hewlett, in the county of Nassau and State of New York, have invented a certain new, original, and ornamental Design for a Handle for Vending Machines or the like, of which the following is a specification, reference being had to the accompanying drawing, forming part thereof, wherein—

Fig. 1 is a side view of my new design;

Fig. 2 is a front view thereof.

I claim:

The ornamental design for a handle for vending machines or the like, as shown.

JOSEPH H. STEVENSON.
